TUBING CATCHER

Andrew J. Colmerauer, Los Angeles, Calif., assignor to Byron Jackson Co., Los Angeles, Calif., a corporation of Delaware

Application January 29, 1934, Serial No. 708,824

10 Claims. (Cl. 103—219)

This invention relates to tubing catchers and has particular reference to a device for automatically arresting the fall of oil well tubing by expanding the device to cause the same to grip 5 the wall of the well casing, through which the tubing passes, with a wedging action.

Automatic tubing catchers as heretofore made have been characterized by the use of a compressed spring or springs supporting all or a part 10 of the weight of the wedge shaped slip members when the wedges are in the inoperative position. In the event that the tubing should drop unexpectedly, the effect of the force of gravity keeping the slips in the retracted or inoperative position is lessened and the force exerted by the 15 compressed spring becomes effective to prevent the slips from dropping as rapidly as the slip seats, thereby causing the slips to ride up on their seats and engage the well casing with a 20 wedging action, thus arresting the fall of the tubing. An illustration of one such tubing catcher now in common use may be seen in United States Patent No. 1,921,547, issued August 8th, 1933, to N. K. Smith and R. K. Hertel. 25 In this type of tubing catcher with the weight of slips supported on a coil spring, it is obvious that the catcher will be rather long because of the end-to-end position of the spring and slips. Some oil wells contain bent casing in which it is 30 difficult to run a long tubing catcher which, of necessity, must be but little smaller in diameter than the inside diameter of the well casing.

Attempts have been made heretofore to make short catchers to overcome the difficulty set forth 35 in the preceding paragraph. One such construction for short catchers has been to eliminate the spring which supports the slips, as is shown in United States Patent No. 1,706,779, issued March 26th, 1929, to H. E. Grau and A. J. Colmerauer. 40 The trouble with such catchers is that, lacking a spring, they cannot always be depended upon to operate successfully in case of an unexpected drop.

It is an object of the present invention to 45 provide a short tubing catcher having spring actuated slips.

Another object is to provide a tubing catcher having spring actuated slips, but in which the weight of the slips is not directly supported by 50 the spring.

Another object is to provide a tubing catcher in which each slip is actuated by a separate spring, giving the slips an outward thrust without supporting the weight of the slips by the 55 springs.

Other objects and advantages will appear from the following description which refers to the drawings.

In the drawings:

Fig. 1 is an elevation view of a preferred form 5 of tubing catcher in accordance with my invention in which the springs are positioned behind the slips;

Fig. 2 is an elevation view, partly in section, of the same device shown in Fig. 1, taken at a 10 different angle;

Fig. 3 is a cross section of the device taken in the plane III—III of Fig. 2;

Fig. 4 is a cross section taken in the plane 15 IV—IV of Fig. 2;

Fig. 5 is an elevation view of a modified form 20 of tubing catcher in which the slip actuating springs are mounted below the slips;

Fig. 6 is an elevation view, partly in section, of the same device shown in Fig. 5 taken from a 25 different angle;

Fig. 7 is an elevation view of still another modification of the invention in which a spiral spring is employed with a rein to actuate the 30 slip;

Fig. 8 is a detail sectional view showing the 35 construction of the catcher illustrated in Fig. 7;

Fig. 9 is an elevation view of still another embodiment of the invention, in which the slip is 40 suspended from a spring actuated rein; and

Fig. 10 is a detail sectional view illustrating 45 the construction of the tubing catcher shown in elevation in Fig. 9.

Referring first to Figs. 1, 2, 3 and 4, the tubing catcher therein depicted comprises a tubular 50 nipple 1 threaded at each end to receive pipe couplings 2 and 3, respectively, which are adapted to connect the tubing catcher into a string of tubing, not shown. The nipple 1 is provided with an enlarged head 4 which may be an integral part of the nipple or may be a separate member, as shown, welded or otherwise rigidly secured to the nipple. The head 4 is provided with one or more, and preferably three or four, tapered seats 5, the catcher shown having three such seats. Each of 55 the seats has its surface tapered inwardly and downwardly. The tapered surfaces of the seats may have any desired configuration although I have chosen to show the arrangement more fully set forth in United States Patent No. 1,921,547, as 60 it permits the use of slips having a greater length and greater gripping area than other arrangements. The principal feature of this construction is that the seats 5 are tapered both inwardly and downwardly, the angle of taper being such 65

that the length of that portion of the seat indicated at *x* in Fig. 2 intersects the outer surface of the nipple 1 so that the lower ends 6 of the seats extend around the outer surface of the nipple.

- 5 Each of the seats 5 is adapted to receive a wedge shaped slip 7 having an arcuate outer face provided with serrations or teeth 3 adapted to engage the inner surface of a well casing. Each slip has at its lower end an inwardly and downwardly inclined outer surface 9 which seats against a complementary inclined surface 10 formed in the head of the catcher. The upper end of each slip is provided with means for retaining the slip from falling completely out of the seat comprising, in 10 the present instance, an upwardly extending finger 11 having a pair of laterally extending lugs 12 which engage a recess in an actuator 15 to be described. Associated with each slip is a flat bow spring 13 adapted to bear against the inner face 20 of the slip to normally urge the slip outwardly against a well casing. For convenience and to save space, I prefer to provide each slip with a longitudinal recess 14 in the rear face thereof to receive the bow spring 13. The lower end of spring 13 bears against an abutment 22 formed on the lower inner face of the slip and the upper end of the spring is supported and bowed by the actuator 15.
- 25 Actuator 15 is a tubular member adapted to slide up and down on the nipple 1 and is provided with relatively thick walls to give it considerable weight. The slips 7 are individually connected to the actuator 15 by means of the fingers 11 having the lugs 12 thereon, which lugs are supported in enlarged recesses 16 in the actuator, which recesses are at the ends of the slots 17 which receive the fingers 11. This provides a loose connection between the slips and the actuator so that the slips can move outwardly from the nipple as they ride 30 up on the slip seats. The actuator is provided with slots 18 aligned with the slots 17 but higher up on the actuator to receive the ends of the springs 13, which ends are bent outwardly as shown at 19. In order to bow the springs 13 whereby they exert an outwardly directed force upon the lower ends of the slips, the vertical passages 21 in the actuator 15, through which the springs pass, have their lower rear walls spaced 35 outwardly from the nipple 1 to provide abutments 21-a which serve as fulcrums for the springs 13, the lower ends of the springs bearing against the abutments 22 on the slips and the upper ends bearing against the actuator just below the slots 18. It will be apparent that with 40 the construction described the springs are held at their upper ends and bowed outwardly at their lower ends, whereby they press outwardly against the abutments 22 on the lower ends of the slips.
- 45 When the device shown in Figs. 1, 2, 3 and 4 is to be used as an automatic tubing catcher, it is connected in a string of tubing in the usual manner and lowered into the well. Under normal conditions the slips 7 remain in their lower and innermost positions, as shown in Figs. 1 and 2, 50 since although the springs 13 are under tension, the weight of the slips and actuator is sufficient to prevent the springs from pushing the slips up along the tapered seats 10 and out against the well casing. However, if the tubing should part above the catcher or drop unexpectedly, the pressure of the slips and actuator against the seat 10 is reduced sufficiently (as a result of the downward acceleration of the catcher) to permit the 55 springs 13 to force the slips up and outwardly

along the tapered seats 10 and into engagement with the well casing, thereby setting the catcher.

Although the invention has been disclosed in an automatic catcher, it is to be understood that by suitable modifications it can be used to anchor the tubing by providing the catcher shown with an anchor mechanism of any well known type. Thus the catcher shown in the drawings will accommodate the type of anchor shown in Patent No. 1,921,547, which anchor comprises a set of 10 bow springs positioned between upper and lower collars slidably mounted on a lower extension to the nipple 1. The bow springs are adapted to drag in the well casing. The upper collar is provided with a series of upstanding fingers adapted 15 to engage a downwardly depending finger 23 (Figs. 1 and 2) at the bottom of each slip. The catcher is provided with a skirt 24 which is rigidly secured to the nipple 1 and may be an integral part of the head 4, as shown. The skirt 20 24 is provided with a series of alternating grooves 25 and pockets 26. The grooves 25 receive the fingers 23 on the slips. The pockets 26 are adapted to receive the upstanding fingers on an anchor of the type described in the aforementioned patent when the anchor is in the inoperative position. To anchor the catcher, as equipped with an anchor of the type referred to, the tubing would be raised a few inches, rotated to the left 25 a portion of a turn and then lowered. This action would move the upstanding fingers of the anchor out of the pockets 26 and into the grooves 25 where they would be operative to push the slips up into engagement with the well casing. It is to be understood that any other suitable 30 form of anchor may be used in place of that described, the anchor forming no part of this invention.

The tubing catcher disclosed in Figs. 5 and 6 is in general similar to that described in connection with Figs. 1 to 4. Thus, it comprises a nipple 30 having a head 31 rigidly attached thereto and an actuator 32 slidably mounted on the nipple below the head 31. Slips 33 are mounted in seats in the head 31 substantially as described in connection with Figs. 1 to 4. In this instance, however, the slips are slidably held at their upper ends in dovetailed grooves 34, thereby restraining the upper ends of the slips from movement outwardly away from their seats while permitting free outward movement of the lower ends of the slips. In Figs. 5 and 6 the slips 33 are connected to the actuator 32 by flat springs 35 which also serve as connecting reins between the actuator and the slips. Thus the upper end of each spring 35 is coiled around a pivot pin 36 on the lower end of the associated slip and the lower end is secured between an outer abutment 37 and an inner abutment 37-a positioned thereabove on the actuator 32. The reins are secured against vertical movement with respect to the actuator by turning out the lower ends of the springs, which ends engage in recesses 38 provided therefor in the actuator. It will be observed that the springs 35 exert a constant outward force on the lower end of each slip, which force is normally resisted by the abutment 39 on the head which bears against the downwardly and inwardly tapered face 40 on the slip. However, downward acceleration of the catcher reduces the force and gravity acting upon the slips and actuator, thereby permitting the slips to be moved upwardly and outwardly by the springs 35.

The embodiment shown in Figs. 7 and 8 is very similar to that just described in connection with

Figs. 5 and 6. It differs therefrom essentially only in the manner in which the upper ends of the slips are restrained from outward movement and in the construction of the reins and springs.

5 Thus, it will be observed that the upper end of each slip is provided with a finger 40a which is tipped outwardly at its upper end and normally engages an abutment 41 on the head of the catcher. It will be observed that upward movement of the slip permits the inclined outer face of the finger 40a to slide outwardly and upwardly past the abutment 41.

The slip and actuator connecting mechanism shown in Figs. 7 and 8 comprises reins 42, each of which is pivotally mounted at its lower end by a pin 43 to the actuator and is provided at its upper end with a projection 44, which engages a pin 45 in the lower end of the associated slip. Constant spring pressure is exerted on each rein 42 by an associated coil spring 46 which surrounds the pivot 43 on each side of the rein 42. The coil spring is provided at its center with a U-shaped arm 47 which bears against the inner side of the associated rein, and the free ends of the spring 46 are supported in grooves 48 provided therefor in the actuator. The operation of the catcher shown in Figs. 7 and 8 is substantially the same as that of the catcher described in connection with Figs. 5 and 6.

30 Referring now to Figs. 9 and 10, a modification of the invention is disclosed in which the individual slips are suspended from an actuator mounted thereabove by spring actuated reins. Thus, slips 50 are mounted in slip seats on a head substantially as previously described but the lower ends of the slips are provided with fingers 51 which extend into recesses 52 in the head and prevent outward movement of the lower end of the slip when the latter is in its lowermost position as shown. Each slip 50 is provided adjacent its upper end with a recess 53 into which hooks the lower end of a rein 54, the upper end of which is hooked onto a shoulder 55 in an actuator 56 slidably positioned upon the nipple 57 above the head 58 in which the slips are mounted. Each rein 54 is normally urged outwardly by a spiral spring 59 of the general construction described in connection with Figs. 7 and 8.

In the construction described in Figs. 9 and 10, each rein 54 is tensioned by its associated spring 59 so that it tends to throw the upper end of the slip suspended thereon outwardly away from the slip seat. However, the spring tension is so proportioned that it is insufficient under normal conditions to overcome the weight of the slip which, therefore, remains in its lower position as shown in the drawing. However, if the catcher is accelerated downwardly at a substantial rate, the apparent decrease in the weight of the slips is sufficient to permit the springs 59 to deflect the upper ends of the slips outwardly into engagement with the well casing, whereupon the slips engage the casing and anchor the tubing.

Although the drawings disclose a weighted actuator attached to the slips, I wish to point out that in some instances the slips themselves will be heavy enough without the added weight of an actuator to normally hold them in an inoperative position against spring pressure. The word "actuator" is therefore used to define a connecting member which moves all of the slips in unison and which may or may not be a weight member. If the catcher is of the single slip type with a heavy slip, even a connector is unnecessary.

75 It is to be understood that the essential fea-

tures of my invention may be incorporated in tubing catchers differing in the exact construction than those shown in the drawings and that the scope of the invention is to be limited only as set forth in the appended claims.

5 I claim:

1. In a tubing catcher, a member adapted to be connected into and constitute a portion of a string of tubing, and having an upwardly and outwardly inclined slip seat thereon, a slip slideable longitudinally on said seat, an actuator slidably supported on said member and connected to said slip for vertical movement therewith, spring means for urging the slip directly outwardly, means for maintaining said slip inwardly against its seat when the slip is in lowermost position, said last mentioned means releasing said slip for outward movement away from its seat in response to upward movement of said slip with respect to said member.

15 2. A tubing catcher as described in claim 1 in which said means for maintaining said slip inwardly against its seat comprises an upwardly and outwardly inclined bearing face on the outer surface of said slip and a cooperating element secured to said member for contacting said bearing face.

25 3. In a tubing catcher, a member adapted to be connected into and constitute a portion of a string of tubing and having a plurality of upwardly and outwardly inclined slip seats positioned thereon, a slip slideable longitudinally on each seat, an actuator slidably supported on said member and connected to said slips for vertical movement therewith, an individual spring means associated with each slip for urging that slip directly outwardly away from its seat, means for maintaining said slips in their inner positions against their seats when in lowermost position, said last mentioned means releasing said slips for outward movement away from their seats in response to upward movement of said slips with respect to said member.

30 4. In a tubing catcher, a member adapted to be connected into and constitute a portion of a string of tubing and having an upwardly and outwardly inclined slip seat thereon, a slip slideable longitudinally on said seat, an actuator slidably supported on said member above said slip seat and connected to the upper end of said slip for vertical movement therewith, spring means supported by said actuator and bearing against the lower end of said slip for directly urging the lower end of said slip outwardly, means for maintaining said slip inwardly against said seat when the slip is in lowermost position, said last mentioned means including a member bearing against the outer side of the lower end of said slip, whereby the lower end of said slip is released for outward movement in response to said spring force upon upward movement of said slip relative to said member.

35 5. A tubing catcher as described in claim 4 in which said spring means comprises a flat bow spring extending from the actuator down back of the slip and contacting with the slip only at its lower end.

45 6. In a tubing catcher, a member adapted to be connected into and constitute a portion of a string of tubing and having an upwardly and outwardly inclined slip seat thereon, a slip slideable longitudinally on said seat, means for slidably retaining the upper end of said slip against the slip seat, spring means for urging the lower end of said slip outwardly from the slip seat and means for maintaining the lower end of the slip inwardly against its seat when the slip is in its

lowermost position and releasing the lower end of the slip for outward movement away from its seat in response to upward movement of the slip along its seat.

- 5 7. A tubing catcher as described in claim 6 in which an actuator is slidably mounted on said member below said slip and in which said spring means comprises a flat bow spring linking said slip to said actuator.
- 10 8. In a tubing catcher, a member adapted to be connected into and constitute a portion of a string of tubing and having an upwardly and outwardly inclined slip seat thereon, a slip slideable on said seat, spring means for urging said slip directly outwardly away from said seat, and means for slidably holding the slip against its seat, the active force exerted outwardly on said slip by the said spring means being normally opposed and balanced by the active force of gravity on said slip acting in conjunction with said means for slidably holding the slip against its seat, whereby said spring means moves said slip outwardly in response to downward acceleration of said catcher in excess of a predetermined rate.
- 15 9. In a tubing catcher, a member adapted to be connected into and constitute a portion of a string of tubing and having an upwardly and outwardly inclined slip seat thereon, a slip slideable on said seat, means slidably mounted on said
- 20 30 member above said slip seat for free vertical movement along said member, stop means for limiting downward movement of said slidable means with respect to said member, means for normally suspending said slip from said slidable

means against the lower portion of said slip seat when said slidable means is in lowermost position, spring means for urging said slip directly outwardly from said seat, and means for slidably holding the slip against its seat, said spring means exerting insufficient force to move said slip away from said seat against the normal force of gravity on said slip acting in conjunction with said means for slidably holding the slip against its seat but sufficient to move the slip outwardly 10 when the gravitational force acting thereon is in part neutralized by downward acceleration of said catcher in excess of a predetermined rate.

10 11. In a tubing catcher, a member adapted to be connected into and constitute a portion of a string of tubing and having an upwardly and outwardly inclined slip seat thereon, a slip slideable on said seat, an actuator slidably mounted on said member at a level vertically disposed from said slip seat, a link connecting said actuator to the adjacent end of said slip, said link including spring means for urging the slip end of said link directly outwardly, and means for slidably holding the slip against its seat, the active force exerted outwardly on said slip by said 25 spring means and link being normally opposed and balanced by the active force of gravity on said slip acting in conjunction with said means for slidably holding the slip against its seat, whereby said spring means moves said slip outwardly in response to downward acceleration of said catcher in excess of a predetermined rate.

ANDREW J. COLMERAUER.
